US00D822704S

(12) United States Design Patent (10) Patent No.: US D822,704 S
Christiana et al. (45) Date of Patent: * Jul. 10, 2018

(54) DISPLAY SCREEN WITH AN ICON(71) Applicant: ADP, LLC, Roseland, NJ (US)

(72) Inventors: John Christiana, Caldwell, NJ (US); Jennifer Anne Herman, Branchburg, NJ (US); Todd Zimmerman, Red Bank, NJ (US); Wayne C. Lincoln, Jr., Sarver, PA (US); Dominic Gadoury, Denver, CO (US); Dan Kirschbaum, Rockaway, NJ (US); Cynthea Ryder, Ringwood, NJ (US); Leesa Walker, Carlsbad, CA (US); Tricia Squitieri, Lyndhurst, NJ (US); Shreya Shah, Jersey City, NJ (US)

(73) Assignee: ADP, LLC, Roseland, NJ (US)() Term: 15 Years(21) Appl. No.: 29/600,959(22) Filed: Apr. 17, 2017*Related U.S. Application Data

(63) Continuation of application No. 29/548,350, filed on Dec. 12, 2015, now Pat. No. Des. 787,386.

(51) LOC (11) Cl. 14-04(52) U.S. Cl.USPC ..... D14/486(58) Field of Classification Search
